UNITED STATES PATENT OFFICE.

WILLIAM S. MILLS, OF TRUMBULL, CONNECTICUT.

WORK-FEEDING ATTACHMENT FOR SEWING-MACHINES.

1,119,098.

Specification of Letters Patent.

Patented Dec. 1, 1914.

Application filed August 12, 1912. Serial No. 714,500.

To all whom it may concern:

Be it known that I, WILLIAM S. MILLS, citizen of the United States, and resident of Trumbull, in the county of Fairfield and State of Connecticut, have invented certain new and useful Improvements in Work-Feeding Attachments for Sewing-Machines, of which the following is a specification.

This invention relates to improvements in work feeding attachment for sewing machines, and is an improvement upon that type of feeding attachment shown and described in my prior Patent #552,691.

The device is particularly adapted for stitching labels on shirts and other garments, or in fact in stitching pieces of materials of predetermined shapes and sizes upon wearing apparel of various sorts. The construction of my improvement is such as to enable me to stitch on labels of the above class without turning the work while in the machine and by simply moving the work forward, backward and longitudinal of the sewing machine bed in a way to follow and stitch down the outer edges of the label.

My present invention relates more particularly to improved mechanism for receiving and holding the label to be stitched, in proper position to be guided backward, forward and crosswise with relation to the operating needle, to include in said construction a special shaped presser foot that is designed to normally hold the label down firmly upon the cloth to which it is to be attached while the needle is working around the outer edges of the said presser foot, to support this presser foot from the movable part of the attachment while guiding the work over the bed of the machine and with relation to the needle, and in a manner to permit the needle to operate entirely around the presser foot without interfering with said supporting means, and finally to provide means whereby the said presser foot and its supporting means may be automatically operated forward and backward with respect to each other so that at a predetermined time the relative position of the support for the presser foot will change from a forward to a rearward position thereby allowing the needle to entirely encircle the presser foot which remains fixed and stationary with respect to the garment and the label being stitched thereto.

The invention further resides and consists in the construction and novel combination and arrangement of parts hereinafter

more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1, is a plan view of my improved work feeding attachment as it would appear when attached to the bed of a sewing machine, in position for beginning an operation. Fig. 2, is a side elevation of the mechanism shown in Fig. 1, and also illustrating a needle and needle bar of a sewing machine, in position to operate in connection with my improved work feeding attachment. Fig. 3, is a further plan view of my improved work feeding attachment, somewhat like Fig. 1, but with the presser foot and other work supporting parts in a different position. Fig. 4, is a further side view of a part of the work feeding attachment shown in Figs. 1, 2 and 3, the presser foot, however, being in a raised position, the bracket 14 and connected parts being omitted. Fig. 5, is an enlarged detail plan view of the presser foot, its movable supporting bar and guide plate which is pivotally hung to the movable slide 23 shown in Figs. 1, 2 and 3. Fig. 6, is an end view as seen from arrow *a* in Fig. 2. Fig. 7, is a longitudinal vertical sectional view taken on line 7-7 of Fig. 5, looking in the direction of the arrow. Fig. 8, is a vertical cross sectional view taken on line 8-8 of Fig. 5. Fig. 9, is a plan view of an oblong shaped label as it would appear after being stitched to a garment, by my improved work feeding attachment.

For the better understanding of my present improvement, I have herein illustrated that portion of my former device which includes the means for moving the work supporting plates and presser foot in a backward, forward and lateral direction with respect to the bed of the sewing machine head and the needle hole therethrough.

For the purpose of more clearly understanding the mechanism, I will now briefly refer to the parts by reference numerals,

wherein 10 represents the bed of a sewing machine head, and 11 the usual hole through which the needle 12 operates. This needle may be of the usual or any preferred design and as shown is carried in a reciprocating needle bar 13 operatively mounted in the head (not shown) of the machine. For the sake of clearness I have also omitted the other operative parts of the sewing machine head including the shuttle carriage and operating connections.

14 represents a bracket that is secured to the bed of the machine head by screws 15 and which serves to support the operating shaft 16 and upon the upper end of which is mounted an operating handle 17. This shaft may be thus rotated by hand, but in practice it is also provided upon its lower end with a pawl and ratchet connection, not shown, whereby it is rotated automatically step by step during the operation of the machine. A small pinion 18 is mounted upon this shaft (see dotted lines Figs. 1 and 3) in position to engage the racks 19, 20, 21 and 22 that are secured to the longitudinally reciprocating slide 23. This slide, as will be noted, is in turn mounted in a lower slide 24 which is free to be moved in a forward and backward direction or at a right angle to the movement of the first named slide. It will thus be apparent that with the operation of the shaft 16 there will be given to the slide 23 and parts carried thereby, both a forward and backward movement and a movement lengthwise of the bed of the sewing machine head, and that said movements when combined produce a corresponding rectangular movement of the work supporting parts and presser foot.

14 The presser foot and its connected parts include the novel features of this application and will next be described as follows: A bracket 25 is secured to the under side of the forwardly projected portion 26 of the longitudinally reciprocating slide 23. A work supporting plate 27 is secured to the bracket and is moved backward and forward upon the top of the bed of the sewing machine with the several movements of the said slide. 145 A rectangular opening 28 is formed in this plate as represented by the space inside of the rectangular lines 29 shown in Figs. 1 and 3. This opening is substantially the same in size as the opening 30 in the clamping plate 31. The said plate 27 serves to support the garment to which the label is fastened, while the clamping-plate 31 arranged above the guide plate serves to close down on the top of the garment and clamp it against the bottom guide plate 27 so that the two may be made to carry the garment, label and presser foot around during the stitching operation. This clamping plate 31 is secured between the outer ends of the two parallel side members 32, whose inner end por-

tions are connected by a cross piece 33, the said ends of the side pieces 32 are pivotally connected to the outwardly disposed ends 34 of the before mentioned bracket 25. A yoke 35 is secured to the side pieces 32 and serves 70 as a bearing for a spring 36 which is adjustably secured to the upper bracket 37 secured to the before mentioned slide 23. The purpose of this spring and its connections are to impart a downward pressure to the 75 said yoke, its frame and clamping plate 31, whereby the garment will be firmly held beneath the clamping plate and against the work supporting plate. The frame members 32 carrying the clamping plate are pivoted to the ends 34 of the bracket 25 so that the plate may be raised and lowered against the action of the spring 36 for the placement or removal of the garment to which the label is to be attached.

80 As before stated the garment which is represented in Fig. 9, by the numeral 39 and to which the label 40 is stitched, is placed upon the supporting plate 27 and after being adjusted to the position desired for the attachment of the label, is clamped by the plate 31 which is lowered upon it. The labels are formed of a shape and size to correspond with the opening in the clamping plate, and after being placed therein and 85 upon the garment, the presser foot 41 is lowered to hold the label in position during the stitching operations. As will be seen from Fig. 1, the presser foot covers the central portion of the label only and leaves a space 90 between it and the edges of the opening of the clamping plate, in a way to expose the entire outer top edge portion of the label for the operation of the needle.

95 The presser foot is mounted to be raised and lowered to permit the insertion and engagement of the label, and is also provided with means for clamping the label down upon the garment as follows: A guide plate 43 is pivotally connected to a pin 44 in the before mentioned forwardly extended member 26 of the slide 23. This guide plate is provided with two guide brackets 45 and 46 in which an arm 47 is slidably mounted. The presser foot is connected to the outer 100 free end of the arm in a way to be supported thereby. A spring 48 is adjustably connected to the before mentioned bracket 37 and extends forward so that its free end engages the guide bracket 45 in a way to hold the same, the arm and presser foot, down in a manner to clamp the latter against the label and hold it in position while stitching. This presser foot may be connected through 110 a link 49 and lever 50 to be lifted.

115 The operation of stitching a label is begun with the parts in the position shown in Fig. 1 whereupon the presser foot together with the work supporting guide plate and clamping plate are moved toward the 120

125 130

- operator as indicated by arrow *b*. This movement is continued until the rear right hand corner of the label is reached, whereupon the latter and its supporting parts are moved to the right thereby producing the cross stitches along the rear edge portion of the label, bringing the parts to the position shown in Fig. 3. A continued operation of the machine carries the work directly rearward, then across, and then forward again to point of beginning in a way to guide the entire edge portion of the label around in a rectangular manner beneath the operating needle.
- 15 In order to permit the needle to completely encircle the presser foot the supporting arm for the presser foot has necessarily got to be moved with relation to the presser foot so as to clear the needle. This feature is accomplished by arranging a longitudinal shaft 51 in the before mentioned arm 47 and mounting upon it two pinions 52 each of which engage a separate rack 53 upon the guide plate 43. The under edge portion of the arm 47 is slotted to receive the said pinions and racks and whereby the arm is guided backward and forward on the plate and within the guides 45 and 46. The said shaft 51 projects out from the end of the arm 47 and extends through a side block 54 that is mounted to move backward and forward and longitudinally of the presser foot, said presser foot being provided with an elongated opening 55 to permit of the said movement of the block. The block is provided upon its under side with a longitudinal groove 56 to accommodate a rack 57 cut in the top side of the lower portion of the presser foot. A pinion 58 is mounted upon the shaft 51 and is arranged within a recess of the said block 44 in a way to engage the rack 57. The under face of the presser foot is preferably notched as shown in Fig. 7, to better engage the label and clamp it in position upon the garment during the stitching operation.
- From the foregoing it will be noted that the presser-foot is necessarily rigidly supported upon the shaft of the arm and remains in a fixed position with relation to said arm until the shaft is operated, when owing to the pinion and rack connection with the guide plate, the arm is moved with regard to the plate and presser foot. This, of course, necessarily means that the presser foot and guide plate at all times remain in positions corresponding to each other and that the arm is moved with relation to both. The arm is set in the position shown in Fig. 1 in any suitable way for the beginning of an operation and remains in that position until the parts move toward the operator sufficient for the engagement of the arm with the adjustable stop screw 59 mounted in a lug 60 secured to the bed of the sewing machine head. This engagement of the arm with the screw necessarily holds the arm while the guide plate and other parts continue to move forward with relation to the said arm and screw. In other words, the arm is shoved back in the ways of the presser foot and guides 45 and 46 so that the end of the arm connected with the presser foot is moved back, so as to be connected with the rear portion of the presser foot as shown in Fig. 3, instead of the front portion, as shown in Fig. 1. It will thus be obvious that when the parts continue to move around and the needle works up to the finishing point, the arm will still be in said relatively rear position and is sufficiently out of the way to permit the needle to finish up against the beginning end of the row of stitches.
- Having thus described my invention, what I claim and desire to secure by Letters Patent is:—
1. A work feeding attachment for sewing machines, comprising slideable work carrying plates, a presser foot to engage the work, a support for supporting the presser foot that holds it in a fixed position with relation to the plates during the stitching operation, and means for moving the presser foot support longitudinally with respect to the presser foot while the sewing machine is in operation.
  2. A work feeding attachment for sewing machines, comprising slideable work carrying plates, a presser foot to engage the work, an arm for supporting the presser foot in a fixed position with relation to the plates, and means for moving the supporting arm forward with respect to the presser foot while the sewing machine is in operation.
  3. A work feeding attachment for label sewing machines, comprising a reciprocating slide, a supporting plate attached thereto, a clamping plate having an opening therein, a presser foot adapted to work through the opening of the clamping plate, means for supporting the presser foot central within the opening during the entire stitching operation, and means for changing the relative location of the support for the presser foot with each label stitching operation.
  4. A work feeding attachment for sewing machines, comprising work carrying plates, a presser foot to engage the work, an arm for supporting the same central with relation to the plates, means to permit the arm to be raised and lowered, and means for moving the said arm with respect to the foot and plates while the sewing machine is in operation.
  5. A work feeding attachment for sewing machines, comprising a reciprocating slide, a supporting plate attached thereto, a clamp-

ing plate having an opening therein, a presser foot adapted to work in and central of the opening of the clamping plate, yieldable connections for holding the foot 5 central in said opening during the entire stitching operation, movable supporting means for the presser foot whereby the relative location of the connection of said means with the presser foot may be changed with 10 each label stitching operation.

6. A work feeding attachment for sewing machines, comprising a reciprocating slide, a supporting plate attached thereto, a clamping plate having an opening therein, 15 an elongated presser foot adapted to work through and central of the opening of the clamping plate, an arm having a movable connection with the presser foot for supporting the same central whereby the point 20 of the connection with the foot is moved longitudinally of the presser foot without disturbing the relative position of the latter.

7. A work feeding attachment for sewing machines, comprising a reciprocating slide, 25 a supporting plate attached thereto, a clamping plate having an opening therein, means for moving the said slide and connected plates in a rectangular direction, a presser foot arranged central of the opening and also adapted to be moved with the 30 said plates, an arm for supporting the presser foot, means for also moving said arm with respect to the presser foot to change the location of the connection of said arm 35 with the presser foot and without disturbing the central position of the latter.

8. A work feeding attachment for sewing machines, comprising slideable work carrying plates having openings therein, a presser 40 foot that is held central thereon to engage the work, an arm normally connecting with one end of the presser foot for supporting the same, and means for moving the arm and presser foot with respect to each other 45 while the sewing machine is in operation and so as to not change the position of the presser foot with relation to the plates.

9. A work feeding attachment for sewing machines, comprising slideable work carrying plates, a presser foot to engage the 50 work, an arm for supporting the presser foot, rack and gear connections of the arm and presser foot, and means for operating the gear to move the presser foot laterally 55 with respect to the arm while the sewing machine is in operation.

10. A work feeding attachment for sewing machines, comprising a reciprocating slide, a supporting plate attached thereto, 60 a guide plate, an arm mounted therein and having gear and rack connections therewith, a clamping plate having an opening therein, a presser foot adapted to work centrally

through the portion of the opening of the clamping plate, and means carried by the 65 said arm for moving the presser foot whereby the relative location of the connection with the foot may be changed with each operation of the machine.

11. A work feeding attachment for sewing 7 machines, comprising work carrying plates, a guide plate connected therewith, an arm slideable upon the guide plate, a presser foot mounted upon the arm and central with respect to the plates to engage 75 the work, means for moving the arm upon the plate, and means for moving the said arm with respect to the presser foot while the sewing machine is in operation.

12. A work feeding attachment for sewing 80 machines, comprising a reciprocating slide, a supporting plate attached thereto, a clamping plate also carried by the slide and having an opening therein, a presser foot adapted to work through the opening 85 of the clamping plate, a guide plate also carried by the slide, an arm movably mounted on the guide plate, a gear and rack connection of the arm and presser foot whereby the relative location of the connection 90 with the presser foot may be changed with each operation of the machine.

13. A work feeding attachment for sewing 95 machines, comprising a reciprocating slide, a guide plate attached thereto, a presser foot the position of which remains fixed with relation to the plate, a slideable arm mounted upon the guide plate and having a movable connection with the presser 100 foot for supporting the same, means for sliding the arm and moving its connection with the presser foot longitudinally and without changing the position of the presser foot.

14. A work feeding attachment for sewing 105 machines, comprising a reciprocating slide, a guide plate hinged thereto, a clamping plate having an opening therein, means for moving the said slide and connected parts in a rectangular direction, a presser 110 foot also adapted to be moved with the said plates, an arm mounted on the guide plate for supporting the presser foot, rack and gear connections of the arm and guide plate, 115 rack and gear connections of the arm and presser foot to change the location of the connection of said arm with the presser foot.

Signed at Bridgeport in the county of 120 Fairfield and State of Connecticut this 10th day of August A. D. 1912.
